CONCEALED HINGE

Louis W. Phiel, Elyria, Ohio

Application February 15, 1935, Serial No. 6,762

1 Claim. (Cl. 16—135)

My invention relates generally to a hinge such as may be used for hanging a door on a door post, and particularly to an arrangement and construction of such a hinge whereby the same will be concealed from either side of the door while the door is in the closed position, and an important object of my invention is to provide a simple and inexpensive hinge of the character indicated which is easy to install and is adequately strong and mechanically efficient.

Other objects and advantages of my invention will be apparent from a reading of the following description in connection with the drawing, wherein for purposes of illustration I have shown a preferred embodiment of my invention.

In the drawing:—

Figure 1 is a horizontal sectional view through a door and door post showing an application of the invention thereto and showing the open position of the door in dotted lines.

Figure 2 is a group perspective view of the elements constituting the hinge per se.

Referring to the drawing in detail, the numeral 5 refers generally to a door post or the like and the numeral 6 to a door swung or hinged thereon. The edge of the door post 5 is cut away as indicated at 7 to receive an element of my hinge, and the corresponding edge of the door 6 is recessed as indicated at 8 to receive other portions of the hinge.

The hinge comprises the generally U-shaped element 9 which is here shown of rectangular formation but may have other suitable formation and cross section retaining in general outline the U-form. The element 9 is composed of the flat plate part 10 which has a suitable number of screw or bolt receiving holes 11 for accommodating screws 12 for attaching the same in position in the cut away portion 7 of the door post 5. The bridge portion 13 of the element 9 may be of suitable shape and form to form the bridge between one edge of the plate 10 and a corresponding edge of the plate 14 which is generally parallel to the plate 10 and foreshortened so that the upper and lower barrels or pin-receiving eyes 15 and 16 which are attached to the outer end thereof come into alignment with the corresponding end of the plate 10 as clearly indicated in Figure 1. The barrels 15 and 16 are arranged to receive therethrough the hinge pin 17 which preferably has on its upper end a head 18 to rest on the upper end of the upper barrel 15 when in place.

When attached to the door post 5 the element 9 has the portion 13 thereof extending consid-

erably outwardly of the cut out portion 7 and into the recess 8 in the door 6 to a point near the inner end of this recess as shown in Figure 1.

The hinge pin 17 traverses a barrel or eye 19 similar to the barrels 15 and 16 located laterally on one end of the leaf which is generally designated 20 and is provided with the screw or bolt holes 21 which receive the screws 22 which attach the element 20 to the inner end of the recess 8 in the door. Only sufficient clearance 10 need be provided between the element 20 and the plate 14 of the element 9 to give sufficient room for proper action of the parts. If desired clearance between these parts may be practically entirely eliminated so that the element 20 may engage the parallel facing portion 14 when the door is in the closed position to prevent farther swinging of the door in one direction.

It will be observed that the sides of the recess 8 closely approach the portion 13 of the element 9 and the barrels, but that notwithstanding this close compact arrangement, free action of all of the parts is assured. The compactness of the arrangement is obviously particularly advantageous where the door and the door post, as in cabinets are of small cross section. The screw or bolt fastener holes 11 and 21 being in the same zone with the pin 18 and its eyes 15, 16, 19 and with the hinging plate 14, the hinge has a relatively-small vertical depth without sacrificing its 30 strength or security of attachment and it can be manufactured at a relatively low cost.

It will be observed that the door post 5 is angularly cut away as indicated at 23 to provide the necessary clearance for the edge of the door 6 when the door is swung to the open dotted line position indicated in Figure 1, which action of the door would otherwise be impeded. It is to be observed that no part of the hinge is visible while the door is in the closed position except that which might be revealed upon close inspection by looking through the crevices separating the door and the door post, which in most cases will be very small. It will also be observed that when the door 6 is swung toward the open position, one side of the hinged edge of the door enters between the portions 10 and 14 of the U-shaped element 9.

Although I have shown and described herein a preferred embodiment of my invention, it is to 50 be definitely understood that I do not desire to limit the application of the invention thereto, and any change or changes may be made in materials, and in the structure and arrangement of the parts, within the spirit of the invention and 55

the scope of the subjoined claim. It is obvious that the locations of the members 9 and 20 might be exchanged and reversed without involving invention.

6. What is claimed is:—

A door hinge comprising a U-shaped connecting member disposed horizontally and having one leg portion adapted to be secured to a door

frame and the other leg adapted to be recessed in an adjacent edge of a door, a hinge leaf adapted to be secured to the door and also adapted to be recessed in said edge of the door inwardly of the recessed leg and a pivot connection between the 5 terminal of the last mentioned leg of the connector and one edge of said leaf.

LOUIS W. PHIEL.
